(57) **CLAIM**

The ornamental design for a bird cape, as shown and described.

DESCRIPTION

FIG. 1 is a front perspective view of a bird cape, showing my new design, shown in use;

FIG. 2 is a side elevational view thereof, shown in use;

FIG. 3 is a front elevational view thereof;

FIG. 4 is a rear elevational view thereof;

FIG. 5 is side elevational view thereof;

FIG. 6 is a top plan view thereof; and,

FIG. 7 is bottom plan view thereof.

The broken lines depicting the human form and parrot in the drawings are for illustrative purposes only and form no part of the claimed design.

The dashed lines shown on the article represent a stitching line.
